UNITED STATES PATENT OFFICE.

BENJAMIN ROSENTHAL, OF NEW YORK, N. Y.

INDEX OR ORDER SHEET AND PAD.

Application filed May 10, 1926. Serial No. 108,080.

The object of my invention is the provision of an article of use in the household, especially in the kitchen, although, as will appear, it may be used in other connections. 5 It is, more specifically, to provide a detachable index or order sheet put up in the form of a pad, and attached to the wall, whereby when the housewife finds that some necessary commodity is lacking, she may note the 10 fact on said sheet and when she next goes to do her shopping, detach said sheet whereon is noted which commodities she is in need of and thus do her ordering in accordance with the notations on said sheet. Furthermore, 15 the object is to provide an improved means for noting the absence of said desired commodity whereby the housewife, without pausing in her duties to hunt for a pencil or pen may immediately note the absence of 20 the desired commodity.

The object of this invention is further to provide an arrangement of said sheet whereby an advertisement may be conspicuously printed thereon so that said sheet will be 25 distributed gratis by the advertiser to the housewife in order to advertise himself. Other objects will be brought out in the description.

These objects are attained by the means 30 illustrated in the accompanying drawing, wherein

Figure 1 is an elevation of the sheet as attached to the pad, and

Fig. 2 is a bottom view of said pad.

Similar numerals and letters refer to similar parts throughout the specification and drawing.

The sheet A is the top sheet of the pad P. All the sheets are attached as in an ordinary 40 pad to a binder C, and backing C', said binder having a means D to attach the pad to the wall of the kitchen or the like. The sheet A, in the embodiment illustrated, is white, while the immediately following sheet B is, for instance, pink or red, as shown in Fig. 1 by vertical lines.

The difference in coloring of the sheet is an important part of my invention. The following sheets also similarly alternate in contrasting colors. All the sheets have a 50 line of perforations 1 parallel to and adjacent the free edge 2. Each sheet is provided with slits 3 which extend perpendicularly to the edge and as far as the perforated line 55 1. It is seen that two successive slits will form between them a strip 4 which will tear

off along the perforated line. The sheet is further provided with a list of names 5 extending parallel to and close to the perforated line, each name being in line with one 60 of the strips 4. The sheet is further provided with an advertisement as 6 and other data as 7 may be provided in any convenient manner. Both sides of the sheet may be made alike. Each sheet, as A, has its free 65 edge, as 2', extending slightly beyond the similar free edge, as 8', of the sheet directly following, as B, the result being a beveled edge of the pad as shown in Fig. 2.

The article described is used as follows. 70 The sheets being hung on the wall, when the housewife notes the absence of the desired commodity, she tears off that strip which is opposite the desired article. In the drawing, for example, the need of both aspirin 75 and rouge has been noted, the strips opposite both having been torn away. Due to the extending of edge 2' beyond edge 8', the strip may be more easily grasped to be detached. The sheets are contrastingly colored so that 80 the fact of a particular strip being torn away will be conspicuously shown and immediately noted so that during the course of her duties if the housewife forgets or is in doubt as to whether she has noted the need 85 of a certain article, a casual glance at the sheet will immediately tell her. Were the sheets of the same color, it would be more difficult to see and require much closer attention to note that a certain strip has been torn 90 away. In other words, the sheet underneath, by its contrasting color, aids to inform the housewife that a particular strip is or is not torn away.

While I have described a preferred embodiment of my invention, it may obviously be used in other connections and I do not wish to be restricted to the particular embodiments shown and described. The names of the articles on the sheet may be any ones 95 desired and the invention may be used in the same or an equivalent form in restaurants, hotel kitchens, retail stores, and the like, obviously not being restricted for use in the household.

I claim:

1. An article comprising a plurality of sheets arranged in the form of a pad, a plurality of detachable tabs at the edge of each sheet, a list of names provided on the sheet 100 adjacent the tabs, each name of the list being opposite a corresponding tab, whereby 110

the absence of a tab denotes a fact concerning the corresponding name, said name remaining on the sheet, similarly facing surfaces of adjacent sheet differing in visual characteristics.

2. An article comprising a plurality of sheets arranged in the form of a pad, each sheet varying in color from the adjacent sheets, a plurality of detachable tabs located 10 at the edge of each sheet, an item associated with each tab, whereby the tearing off of a tab denotes a certain fact regarding said item, the varying color of the sheets serving to show the absence of a tab after removal.

3. An article comprising a sheet provided 15 with a plurality of detachable tabs at the edge thereof, a list of items inscribed on the sheet adjacent said tabs, each item being associated with a corresponding tab, whereby the absence of a tab denotes a certain fact 20 regarding its corresponding item, a second sheet with which the first-named sheet is held in super-imposed relation, said second sheet having a different colored surface than the first-named sheet, the varying colors of 25 said sheets serving to show the absence of a tab after removal.

BENJAMIN ROSENTHAL.
